CLAIM

The ornamental design of a thermocouple and RTD connector, as shown and described.

DESCRIPTION

FIG. 1 is a front isometric view of the male portion of the connector showing our new design;
FIG. 2 is a rear isometric view thereof;
FIG. 3 is a top plan view thereof;
FIG. 4 is a rear elevation view thereof;
FIG. 5 is a front elevation view thereof;
FIG. 6 is a side elevation view thereof;
FIG. 7 is a bottom plan view thereof;
FIG. 8 is a front isometric view of the female portion of the connector showing our new design;
FIG. 9 is a rear isometric view thereof;
FIG. 10 is a top plan view thereof;
FIG. 11 is a rear elevation view thereof;
FIG. 12 is a front elevation view thereof;
FIG. 13 is a side elevation view thereof;
FIG. 14 is a bottom plan view thereof;
FIG. 15 is a front isometric view of the connected male and female portions of the connector showing our new design; and,
FIG. 16 is a front isometric view of the disconnected male and female portions of the connector showing our new design.
